TYPEWRITING MACHINE

Louis C. Antrim, New York, N. Y., assignor to
Autographic Register Company, Hoboken, N. J.,
a corporation of New Jersey

Application February 17, 1939, Serial No. 256,955

11 Claims. (Cl. 197—133)

This invention relates to typewriting machines, and more particularly, to the type of machines for doing tabulating work.

With such machines, punched cards control the typewriting and printing operations which are performed on continuous strips, usually comprising a succession of forms which may be bills, invoices, or the like.

There are variable amounts of typewriting to be done on each form, but the "Carroll" carriage of the manufacture and sale of the International Business Machines Corporation contains mechanism for ejecting the form when the last item has been written thereon and to bring the first line of writing on the next form to writing position.

Heretofore, many attempts have been made to feed a plurality of webs through this typewriter carriage and to maintain the webs in alignment with each other and in coordination with the machine. Such attempts have been unsuccessful for two reasons—first, because the strips, in order to keep them in registration, had to be provided with pinwheel-engaging apertures so as to be positively fed; and, second, because the mechanism of the machine was incapable of sufficiently accurate adjustment to feed the strips exactly to the first line of writing at each operation. The mechanism was nearly perfect, but there was always a slight discrepancy in the ejecting feeding motion, and this was cumulative, with the result that the operator had to frequently readjust the strips relative to the platen of the machine.

These difficulties are avoided by the present invention, which is a species of the inventions disclosed in my application Serial No. 246,263, filed December 17, 1938, now abandoned, my application Serial No. 255,243, filed February 8, 1939, now abandoned, and my application Serial No. 372,100, filed December 28, 1940, said last application containing all that is contained in the two earlier applications, by controlling the feeding operations of the strips by photoelectric means so that upon each operation of the ejecting mechanism, the form to be written upon, is brought to a definite predetermined position controlled by physical characteristics of the strips themselves. With this feeding mechanism, slight but unobjectionable discrepancies in the location of the form at the first line of writing may occur, but, since the strips are brought to a definite position and arrested there under control of the physical characteristics located at

form-length intervals on the advancing strips, the discrepancy is not cumulative.

In the form of the present invention at present preferred, the strip or strips of a superposed pile of strips, which may or may not be secured together but are fed as a unit through the machine, are provided at form-length intervals therealong with a physical characteristic, preferably in the form of a light-absorbing or non-reflecting portion. These nonreflecting portions can be formed on the strips during the printing operation in which the succession of forms are printed thereon by making a dot or other shape of black or other light-absorbing color on the back of the strip. Also, this portion may be formed by providing the strips with cutouts which pass over the black or nonreflecting surface of the table, or the strips can be provided with cutouts and have a continuous carbon strip which will be exposed through the cutout to provide a nonreflecting portion on the strip.

These portions of the strip, as they pass through the machine with the strips in a predetermined path, will prevent a light beam from reflecting from the strip to a light-sensitive cell when they reach a predetermined point in the machine, which may be varied according to the length of the form for the place where the first line of writing occurs. An electric circuit is controlled by the detection of one of these portions by the light-sensitive cell which results in the releasing of the feed rollers so that further feeding of the strips ceases. At the same time, the strip is engaged by a brake which stops its advance and prevents overthrow. With a control of this type, it is not necessary to provide feeler contacts which ride on the strips or other means in engagement with the strips which might injure the strips or otherwise be undesirable.

One of the important features of the present invention is the provision of means for controlling the ejection of a written form and the location of the next form in writing position in such a way that it may be applied as an attachment to existing machines, and in such a way as not to disturb the electrical or mechanical parts of the machine. This is done by causing an existing part of the machine, which moves when the mechanical ejector of the machine is operated, to close a switch through the electrical control provided by the present invention. The only thing which need be done to the "Carroll" carriage is to manually adjust the mechanism, for regulating the quantity of ejection, in the way

provided for in the machine, to the maximum, or at least to such points sufficiently beyond the length of the form that are being used in the machine as to assure some idle operation of the ejector mechanism beyond what is needed to feed the forms.

Any suitable electrical arrangement and mechanism for releasing the feed rollers may be employed. If desired, the control can be in a low voltage circuit and operate the solenoid for releasing the feed rollers and clamping the paper.

In the broader aspects of this invention, the feeding mechanism may, if desired, be the positive type, including pins engaging pin-apertures in the paper so as to maintain the paper strips in registration with one another. However, it is desirable to omit these mutilating apertures, and, according to the present invention, the paper strips, including the interleaved carbon strips, may be suitably stapled together to travel through the machine as one. When the paper strips so stapled together are fed frictionally, creeping occurs between the several strips, but the amount of creep resulting from the feeding of one form-length is imperceptible and not objectionable. With the strips stapled together, this creep is accumulated in advance of the next staple, and when the feed mechanism is released to interrupt the ejection of the strips, the strips are relieved of frictional engagement with each other, with the result that the strips themselves shift relatively and come into registration as defined by the next staple.

Other features and advantages will hereinafter appear.

In the accompanying drawings:

Figure 1 is a top plan view of the machine.

Fig. 2 is a side elevational view of the machine with the attachment in place.

Fig. 3 is a longitudinal section, taken along line 3-3 of Fig. 1.

Fig. 4 is a diagrammatic view of the device showing the rollers in feeding relation.

Fig. 5 is a view similar to Fig. 4, showing the characteristic on the strip in intercepting relation, with the light beam and the feed rollers in raised position.

Fig. 6 is a diagrammatic view of the control view of the control unit, showing the circuit for operating the solenoid.

Fig. 7 shows a modified form of the strip as used in the machine.

The attachment of the present invention is adapted to be readily applied to a standard tabulating machine without disturbing or removing the electrical or mechanical parts of the machine. It is illustrated as being applied to a machine 20, having a "Carroll" carriage, of the manufacture and sale of the International Business Machines Corporation.

As is well known in machines of this type, continuous strips of stationery 21 may be utilized. In the preferred form of the invention, the strips 21, which may or may not have a succession of printed forms thereon, are secured together at form-length intervals by staples 21a which are driven through the continuous strips whereby the strips are fed through the machine as a unit. These strips are provided at form-length intervals with non-reflecting portions so that light projected thereon will not be reflected therefrom, for a purpose to be later described.

These nonreflecting portions can be in the form of dots 22 or other configurations of light.

absorbing ink which are placed on the strips in predetermined relation to the form thereon during the printing operation, or they can be apertures 22a cut in the strips at the time the forms 5 are printed thereon and in predetermined relation with said forms. These portions, of course, will not reflect the light projected on the sheet, and this is especially true if they are carried over a light-absorbing surface, or are interleaved with 10 transfer material, such as carbon paper or the like, which will be, of course, nonreflecting.

The strips pass through the machine, around a platen 23 and under a pressure roller 24 co-operating therewith. The printing mechanism of the machine indicated as a type bar 25 is automatically controlled, through mechanism not shown, by a card having suitably arranged apertures representing predetermined data, the machine scanning the data from the card and automatically controlling the writing mechanism to translate this information into impressions on the continuous strip. During the writing operation, the platen is automatically advanced line-by-line until all of the required data is inserted 20 on the form.

The machine of the type described is provided with ejecting means, indicated generally at 26, for quickly rotating the platen and feeding the form from the machine after the writing operation has been completed and presenting the first 30 line of writing of the next form in writing position.

The operation of the ejecting mechanism in this type of machine is initiated by a suitably 35 located hole in the card so that the controlling mechanism, upon reaching this hole, immediately puts the ejecting mechanism into operation to rotate the platen and quickly feed the form out of writing position. Mounted on the side of the machine is a movable part 27 which is operated by the ejecting mechanism during the ejecting period to move outwardly and remain in extended position throughout the period.

The ejecting mechanism can be adjusted so as to advance the strip a definite number of inches so as to present the line of writing on the next form in writing position.

In actual practice, it has been difficult and almost impossible to adjust the mechanism so that it places the first line of writing exactly in line of position in each operation thereof, and the error in such adjustment during the operation of the machine accumulates so that before very long the position of the strip in the machine must be manually adjusted by the operator, thus requiring the attention of the operator to see that the succeeding forms are in proper position, and, if not, correcting the error.

The attachment of the present invention locates each form individually in proper position, and, therefore, eliminates the accumulated error in the ejecting of the sheets, thus rendering it unnecessary for an operator to be constantly watching the machine and manually correcting the error.

The front portion of the attachment of the present invention is similar to that shown in my copending application Serial No. 246,263, and comprises a pair of side plates 30, 31 secured together by a plurality of rods 32, 33 to form a unit. The side plates are each provided with a notch 34 in the front edge thereof and another notch 36 in the bottom edge, which notches are located so as to fit over existing studs 37, 38

on the frame of the machine and are locked thereto by a pivoted latch 39.

A pair of feed rollers 40, 41 are mounted on shafts 42, 43 extending between the side plates for feeding the continuous strips through the machine. The feed roller 41 is geared to the platen of the machine through suitable gearing 44 (Fig. 2) so as to be rotated when the platen is driven from the automatically controlled driving means. The pressure of the roller 40 on the platen is relieved so that the platen, when rotated, will not feed the strip, all of the feed being accomplished by the feed rollers.

The shaft carrying feed rollers 40 is carried by a pair of arms 45 pivotally mounted on the side plates. The rollers 40 are normally urged into engagement with the roller 41 by a spring 46. The actuator for moving the rollers 40 out of engagement with the roller 41 comprises a pair of arms 47, 48 secured to a rod 49 journaled in the side plates. These arms have blocks 50, 51 which engage the arms 45 and move the rollers 40 away from the roller 41 when the arms 47, 48 are moved downwardly, thus stopping the feeding. The arm 48 has a rearwardly extending part 48a by which it is actuated in a manner to be described.

In order to control the operation of the feed rollers, a novel control unit is provided which will cooperate with the strips to properly locate the first line of writing on the succeeding form in writing position. The control unit of the present invention is mounted on the back of the machine so as to cooperate with the continuous strips as they enter the machine. The control unit comprises a pair of side plates 60, 61 secured together by a pair of rods 62, 63, extending transversely of the machine.

As shown clearly in Fig. 3, this part of the attachment is secured to the machine by having each of the side walls provided with a notch 64 on its forward face adapted to be slipped endwise over an existing stud 65 on the side walls of the machine, and a notch 66 opening on the undersurface adapted to engage and be supported upon another stud 67 carried by the side walls of the machine. A latch plate 68 is pivoted to the side plates, and is provided with a hooked portion 68a adapted to engage under the second stud and hold the unit in place on the machine.

In order to properly locate the strip in writing position, the present invention provides a means mounted on the attachment and controlled by the advancing strip for rendering the feed rollers inoperative to continue feed when the strip has reached proper writing position.

While this may be accomplished in many ways, in the preferred form of the invention a control means, which includes a light-sensitive means, is spaced from the strip so that control means does not engage the strip during its passage through the machine. The light-sensitive means will be controlled by the position of the nonreflecting portions of the strip and actuate a means to immediately stop the advancing of the strip upon the detection thereof.

As shown in Fig. 1, a channel member 69 extends across the space between the side plates 60 and 61 so as to form a table 70 over which the advancing strips can pass. If desired, this table can have its upper surface coated with a nonreflecting material as shown in Fig. 7. The table has its ends 71 bent up, each end being secured to a block 72 slidably mounted on the upper edge of the side plates as shown in

Figs. 1 and 2. The channel is electrically insulated from the blocks by insulation 73 as shown in Fig. 1.

Disposed between the bent-up ends of channel member 69 is a rod 74 which is secured in place and insulated therefrom. The control unit 75 is slidably mounted on the rod and may be adjusted along the rod transversely of the table and locked in adjusted position by means of set screw 76. The control unit comprises a carrier block 77 slidably mounted on the rod 74 and having an upstanding portion 78 on which is mounted a light source 79 and a light-sensitive or photoelectric cell 80. The light source and cell are enclosed in shields 81 and 82, and another shield 83 is carried by the block and extends toward the strip so as to prevent undesired rays of light from actuating the cell. The beam of light from the light source is focused on the strip by a lens or the like 84 and is reflected therefrom to the light-sensitive cell.

The table and the control unit carried thereby can be adjusted on the attachment to properly locate the control unit so that the beam of light will engage the strip in the path of the movement of the nonreflecting portions of the strip as the strips pass through the machine.

In order to define the path of the strips through the machine, suitable guides 85 are adjustably mounted on the rod and have dependent fingers 86 to engage the side margins of the strips. Additional guides 87 are adjustably carried by the rods 32, 33 at the front portion of the attachment and engage the sides of the strips.

The circuit for controlling the feeding means includes a pair of contacts 90, 91 which are operated by a relay 92. The relay is connected to the photoelectric cell through an amplifier 93 so as to be actuated thereby.

As shown in Fig. 6, the amplifier can be of the type including a thermionic tube 94 having the grid 95 thereof connected to the photoelectric cell, and when the cell is illuminated the grid will be biased so that current flows in the relay circuit and moves the contact 91 to the position shown in Fig. 4, thus holding the control circuit open. The contact 91 is normally urged to closed-circuit position with contact 90 by a spring 93.

As soon as the nonreflecting portion of the strip passes under the beam, no light will be reflected to the cell, and the relay will be deenergized and release the contact 91 which will be moved into closed-circuit position to stop the feeding of the strip. The stopping of the feed of the strip is accomplished by securing to the arm 48a an armature 94 which is adapted to be received in the core of a solenoid 95 carried by the rear part of the attachment and connected in the control circuit.

As soon as the nonreflecting portion of the strip passes into the beam and the light prevented from being reflected to illuminate the light-sensitive cell, the relay will be released and the contacts moved into closed-circuit position by the spring.

The solenoid will be energized and will draw the armature into the core pulling the arms 47, 48 downwardly so that the blocks 50, 51 engage the arms 45 and move the pressure rollers about their pivotal mounting away from the feed roller to stop the feed of the continuous strip.

To prevent the operation of the feed-arresting means at any time except during the ejecting periods, the control circuit is provided with a monitor switch 96 which is closed only during the

ejecting period. As described in my copending application, the switch is a normally open switch and is moved to closed-circuit position and held in this position by the movable part 27 of the ejecting mechanism which is moved during the ejecting period.

When the attachment is applied to the machine, the ejecting mechanism is adjusted in such a manner that it will at least have a short idle period after the pressure roller has been released. In other words, instead of ejecting for a ten-inch form, the mechanism is set for a twelve-inch form, so that there is sufficient operation of the feed roller during the ejecting period to insure proper positioning in the strip.

In order to prevent the sheets from feeding during the idle operation of the platen and roller 41 driven thereby, means are provided for positively stopping the strip. This means, in the present invention, is similar to that shown in the said copending application, and comprises a normally inoperative brake 97 insulatedly carried by the rod 14 mounted between the ends of the member 88 having an actuator 98 which is operated by the arm 48a when it moves to release the feed rollers. In this manner, the brake is applied simultaneously with the separation of the feed rollers.

The operation of the control is as follows:

After the writing operation is completed, the ejecting mechanism is initiated to drive the platen to eject the strip. The feed rollers 40, 41 of the attachment will be driven from the platen and will continue feeding of the strip over the platen from writing position. The transversely extending channel member 69 with the elements carried thereby will have been adjusted along the top edges of the side plates 60, 61 to properly locate the control unit so that it will be in proper position with respect to the writing position of the machine to cause the light beam to be intercepted by the nonreflecting portion of the strip and stop the next form in writing position. The control unit will have been adjusted transversely of the continuous strip so that the beam will be projected on the strips in the path of movement of the nonreflecting portions.

The ejector mechanism will drive the feed rollers which will draw the continuous strips over the platen. As soon as the ejector mechanism is operated, the movable part 27, actuated thereby, will close the monitor switch and establish the control circuit including the contacts 90 and 91, and, upon the control unit detecting the nonreflecting portion of the strip, the contacts will close and complete the circuit to the solenoid which will cause the armature to be drawn into the core and pull down the actuating arms for releasing the feed rollers from feeding relation with the strip, and also operate the brake to instantly stop the continuous strip with the form in proper position.

While it is true that the adjustment is such that the first line of writing may not be in an accurately determined position, such error will not be cumulative, as each form is located separately and independently.

The ejector mechanism will continue to operate for the duration of the ejecting period, but, inasmuch as the pressure roller is out of engagement with the feed roller, the strip will not be fed.

As soon as the ejector mechanism has completed its period of operation, the movable part carried thereby will release the monitor switch and open the circuit to the solenoid, whereupon

the pressure roller again engages the feed roller, and the strips will again be fed line-by-line during the normal operation of the machine throughout the writing operation, the circuit for the control mechanism remaining open until the next ejecting period.

If the strip shown in Fig. 7 is used, having two nonreflecting portions, two control units can be used therewith and the relays connected so that both of the control units must have released the contacts before the strip will be stopped. This will insure against accidental operation of the control unit making, in effect, one unit check upon the other.

15 In the broader aspects of the invention, the control circuit, including the solenoid and contacts, can be a low voltage circuit, while the control unit is energized by a higher voltage. Also, it may be desired to control the light source

20 so that it is illuminated only during the ejecting period, and, when this is the case, the circuit to the light should be controlled by the monitor switch, and the control circuit including the solenoid be designed with a sufficient time lag that the solenoid will not operate before the relay has had an opportunity to attract the contact 91 and open the circuit.

25 Variations and modifications may be made within the scope of this invention and portions of the improvements may be used without others.

I claim:

1. In a typewriting machine of the type described, an attachment having feeding means including a pair of feed rollers for feeding a continuous strip through the machine, said strip having a succession of printed forms thereon; means for operating the feeding means to quickly eject a form from the machine; photoelectric means carried by the attachment and controlled by the advancing continuous strip for separating the feed rollers to stop the advance of the strip when the first line of writing on the next succeeding form is in proper writing position; normally inoperative brake means carried by the attachment; and means for applying the brake means to the strip simultaneously with the separation of the feed rollers.

2. In a typewriting machine of the type described, an attachment having feeding means including a pair of feed rollers for feeding a continuous strip through the machine, said strip having predetermined nonreflecting portions at form-length intervals; means for operating the feeding means to quickly eject a form from the machine; a normally inoperative brake carried by the attachment; and means carried by the attachment for controlling the feeding means during the ejecting period comprising a light-sensitive cell and a circuit controlled thereby, said circuit including a solenoid for separating the feed rollers and rendering said brake operative to stop the advance of the strip when the first line of writing on the next succeeding form is in writing position, said circuit being closed upon detection by the light-sensitive means of a nonreflecting portion of the advancing strip.

3. In a typewriting machine of the type described, means including a pair of separable feed rollers for feeding continuous stationery through the typewriter, said stationery including a strip provided at form-length intervals with a nonreflecting portion; means for operating the feeding means to eject a form out of the typewriter; means including a light source providing a beam focused on the strip in the path of movement

of the nonreflecting portion; a photoelectric cell adapted to receive the beam reflected from the strip, the nonreflecting portion interrupting the beam when the advancing strip has reached a predetermined position in the machine; and means controlled by the photoelectric cell for separating said feed rollers and stopping the feed, upon the detection of said nonreflecting portion of the strip, whereby the first line of writing on the succeeding form is properly located in writing position.

4. In a typewriting machine of the type described, means including a feed roller and a co-operating pressure roller for feeding continuous stationery through the typewriter, said stationery comprising strips provided at form-length intervals with a portion which does not readily reflect light; means for operating the feeding means to eject a form out of the typewriter; means including a light source providing a beam focused on the strip in the path of movement of said portion; a light-sensitive cell adapted to receive the beam reflected from the stationery, the said portion preventing reflection of and interrupting the beam when the advancing stationery has reached a predetermined position in the machine; and means controlled by the light-sensitive means for releasing the pressure roller from co-operative relation with said feed roller and thereby stopping the feed, upon the detection of said portion of the stationery, whereby the first line of writing on the succeeding form is properly located in writing position.

5. In a typewriting machine of the type described, means including a pair of feed rollers for feeding a continuous strip through the machine, said strip having a succession of printed forms thereon and nonreflecting portions at form-length intervals; means for operating the feeding means line-by-line during the writing operation and thereafter continuously during an ejecting period to eject a form from the machine; electro-responsive means for separating the rollers to stop the feed of the strip; means for establishing a circuit to the electro-responsive means during the ejecting period; relay means including means in said circuit for completing the same; and photoelectric means for rendering the relay means operative to close said circuit upon detection by the photoelectric means of a nonreflecting portion of the continuous strip to energize the electro-responsive means to separate the rollers, said circuit establishing means opening the control circuit at the end of the ejecting period.

6. In a typewriting machine of the type described, an attachment having a pair of feed rollers for feeding a continuous strip through the machine, said strip having nonreflecting portions thereon at form-length intervals; means carried by the attachment for separating the feed rollers when the first line of writing on the next succeeding form is in proper writing position; brake means for stopping the advance of the strip when the feed rollers are separated; and means for controlling the means for separating the rollers and brake means including a light source for projecting a beam toward the strip, a light-sensitive cell for receiving the reflected beam, and a relay controlled by the light-sensitive cell for simultaneously actuating both means upon the detection of a nonreflecting portion of the strip, said light source and light-sensitive cell being adjustable relative to the attachment to properly

locate the first line of writing on forms of different lengths in proper writing position.

5 7. In a typewriting machine of the type described, an attachment having a pair of feed rollers for feeding a continuous strip through the machine, said strip having nonreflecting portions thereon at form-length intervals; means carried by the attachment for separating the feed rollers when the first line of writing on the next succeeding form is in proper writing position; means co-operating with the strip for stopping the advance of the strip upon separation of the feed rollers; and means for controlling said first-mentioned means including a control unit having a light source for projecting a beam toward the strip and a light-sensitive cell mounted thereon for receiving the reflected beam, shielding means for the light source and light-sensitive cell mounted on the unit, and a relay controlled by the light-sensitive cell for actuating the means separating the feed rollers upon the detection of a nonreflecting portion of the strip, said control unit being adjustable relative to the attachment to properly locate the first line of writing on forms of different lengths in proper writing position.

15 8. In a typewriting machine of the type described, an attachment having means for securing the same to the machine, said attachment having a rotatable roller over which a continuous strip is led; pressure means for pressing a continuous strip having printed forms thereon into engagement with the rotatable roller to cause said strip to be fed thereby through the machine; means for rotating said roller an amount in excess of that necessary to move the continuous strip to cause the first line of writing on the next form to be properly positioned in the typewriting machine; means including a light source for projecting a beam toward the strip and a light-sensitive cell for receiving the beam reflected from said strip, said strip having means thereon in predetermined relation with the first line of writing on the strip to intercept the beam and vary the illumination of the light-sensitive cell; and means actuated by the variation in illumination of the light-sensitive cell for relieving said pressure means whereby the roller is rendered inoperative to advance the strips.

30 9. In a typewriting machine of the type described, an attachment having means for securing the same to the machine, said attachment having a rotatable roller over which a continuous strip is led; pressure means for pressing a continuous strip having printed forms thereon into engagement with the rotatable roller to cause said strip to be fed thereby through the machine; means for rotating said roller an amount in excess of that necessary to move the continuous strip to cause the first line of writing on the next form to be properly positioned in the typewriting machine; means including a light source for projecting a beam toward the strip and a light-sensitive cell for receiving the beam reflected from said strip, said strip having means thereon in predetermined relation with the first line of writing on the strip to intercept the beam and vary the illumination of the light-sensitive cell; means actuated by the variation in illumination of the light-sensitive cell for relieving said pressure means whereby the roller is rendered inoperative to advance the strips; and means also actuated by the light-sensitive cell for applying a braking action to the paper to hold the same against accidental movement while the pressure is relieved

and the roller rendered inoperative to feed the strip.

10. In a typewriter of the type described, a platen; means for frictionally engaging and feeding continuous stationery having a succession of form-lengths over the platen, said stationery comprising a plurality of record strips interleaved with transfer material, at least one of the exposed strips having predetermined physical characteristics at form-length intervals; means for writing on the continuous stationery; ejecting means for actuating the feeding means to eject the remainder of a form-length from the machine and present the first line of writing on the next succeeding form-length in writing position; means for actuating the ejecting means after the writing operation, said ejecting means being adjustable and adjusted to operate the feeding means to eject a greater length of strip than the form-length being used; and control means spaced from the strip and rendered operative upon the detection of a physical characteristic in the advancing strip for removing the frictional driving engagement of the feed means with the stationery and rendering the feeding means operated by the ejecting means ineffective to continue to feed the

continuous stationery when the next succeeding form is in desired writing position.

11. In a typewriting machine of the type described, means for frictionally feeding continuous stationery through the typewriter, said stationery including strips provided with a succession of printed forms and a nonreflecting portion on each form in predetermined position with respect to the printing of the form; means for operating the feeding means to eject a form out of the typewriter; means including a light source providing a beam focused on the strip in the path of movement of the nonreflecting portion; a light-sensitive means adapted to receive the beam reflector from the paper, the nonreflecting portion interrupting the beam when the advancing stationery has reached a predetermined position in the machine; and means controlled by the interruption of the beam to the light-sensitive means for quickly relieving the friction of the feeding means and abruptly stopping the advance of the strip, upon the detection of said nonreflecting portion of the strip, whereby the first line of writing on the succeeding form is properly located in writing position.

LOUIS C. ANTRIM.
